UNITED STATES PATENT OFFICE.

GOSLEE F. GEIGER, OF LOUISVILLE, KENTUCKY.

DESIGN FOR A SAVINGS BANK.

Application filed March 10, 1926. Serial No. 16,861. Term of patent 14 years.

To all whom it may concern:

Be it known that I, GOSLEE F. GEIGER, a citizen of the United States, and resident of Louisville, in the county of Jefferson and State of Kentucky, have invented a new and original Design for a Savings Bank, of which the following is a specification, reference being had to the accompanying drawing, forming part thereof.

In this drawing:—

The figure is a perspective view of the savings bank.

I claim:—

The ornamental design for a savings bank, as shown.
